CLAIM

The ornamental design for a wallpack luminaire, as shown and described.

DESCRIPTION

FIG. 1 is a front, upward perspective view of a wallpack luminaire;

FIG. 2 is a front, downward perspective view thereof;

FIG. 3 is a left side elevational view thereof;

FIG. 4 is a right side elevational view thereof, the left side elevational view being identical thereto;

FIG. 5 is a rear elevational view thereof;

FIG. 6 is a front elevational view thereof;

FIG. 7 is a bottom plan view thereof; and,

FIG. 8 is a top plan view thereof.

The broken lines represent portions of the luminaire which form no part of the claimed design.
